US0D1029031S

(12) **United States Design Patent** (10) **Patent No.:** **US D1,029,031 S**
(45) **Date of Patent:** **** May 28, 2024**

(54) **DISPLAY SCREEN OR PORTION THEREOF
WITH A GRAPHICAL USER INTERFACE**

20/384; H04L 51/32; H04L 51/52; H04W
4/21

See application file for complete search history.

(71) Applicant: **Snap Inc.**, Santa Monica, CA (US)

(56) **References Cited**

U.S. PATENT DOCUMENTS

(72) Inventors: **Dylan Shane Eirinberg**, Venice, CA (US); **Kyle Goodrich**, Venice, CA (US); **Andrew James McPhee**, Culver City, CA (US); **Daniel Moreno**, New York, NY (US)

(73) Assignee: **Snap Inc.**, Santa Monica, CA (US)

(**) Term: **15 Years**

(21) Appl. No.: **29/909,311**

(22) Filed: **Aug. 3, 2023**

Related U.S. Application Data

(62) Division of application No. 29/788,109, filed on Mar. 16, 2021, now Pat. No. Des. 998,637.

CLAIM

The ornamental design for a display screen or portion thereof with a graphical user interface, as shown and described.

DESCRIPTION

The FIGURE is a front view of a display screen or portion thereof with a graphical user interface, showing our new design.

The broken lines illustrate unclaimed portions of the display screen, and the broken lines form no part of the claimed design.

1 Claim, 1 Drawing Sheet
